UNITED STATES PATENT OFFICE

143,525

DESIGN FOR A HOIST

Victor L. Darnell, Spring Valley, Ohio, assignor to The Master Electric Company, Dayton, Ohio, a corporation of Ohio

Application July 28, 1944, Serial No. 114,607

Term of patent 14 years

(Cl. D41—1)

To all whom it may concern:

Be it known that I, Victor L. Darnell, a citizen of the United States, residing at Spring Valley, Greene County, Ohio, have invented a new, original, and ornamental Design for a Hoist, of which the following is a specification, reference being had to the accompanying drawing forming a part thereof, in which

Fig. 1 is a front perspective view of a hoist showing my new design, and

Fig. 2 is a front elevation thereof.

The left side of the hoist is substantially identical to the right side thereof, as shown in Fig. 1.
The back of the hoist is substantially plain.

I claim:

The ornamental design for a hoist, substantially as shown and described.

VICTOR L. DARNELL.
